UNITED STATES PATENT OFFICE.

DON Z. FLOWER, OF MINNEAPOLIS, MINNESOTA

VALVE MECHANISM FOR INTERNAL-COMBUSTION ENGINES.

1,191,169.

Specification of Letters Patent.

Patented July 18, 1916.

Application filed January 18, 1915. Serial No. 2,929.

To all whom it may concern:

Be it known that I, DON Z. FLOWER, citizen of the United States, residing at Minneapolis, in the county of Hennepin and State of Minnesota, have invented certain new and useful Improvements in Valve Mechanism for Internal-Combustion Engines, of which the following is a specification.

My invention relates to internal combustion engines and more particularly to the valve mechanism therefor.

As an object of the invention I contemplate a suitable cylinder formation whereby to provide for the arrangement of a novel 15 rotatable valve member thereon, said valve member operating to control both intake and exhaust.

A further object of the invention is to decrease the number of working parts and 20 to improve the arrangement of gears and shafts used in the transmission of power from the crank shaft to the rotary valve.

A still further object of the invention is to generally improve the construction and 25 increase the efficiency of an explosive engine of the four cycle type.

The above and additional objects are accomplished by such means as are illustrated in their preferred embodiment in the 30 accompanying drawings, described in the following specification and then more particularly pointed out in the claims which are appended hereto and form a part of this application.

In describing my invention in detail reference will be had to the accompanying drawings, wherein like characters denote like or corresponding parts throughout the several views, and in which:

Fig. 1 is an elevation of an engine constructed in accordance with the present invention; Fig. 2 is a view similar to Fig. 1, one half of the engine being shown in elevation, the view being taken at an angle 45 to that shown in Fig. 1; Fig. 3 is a longitudinal sectional view; Fig. 4 is an elevation of the rotary valve; and Fig. 5 is an end view of the valve.

Referring now to the drawings by numbers, 1 designates the engine cylinder, 2

the piston, 3 the piston rod, 4 the crank shaft, 5 the crank case, and 6 the spark plug of an internal combustion engine, the structure and arrangement of the above referred to parts (except the cylinder) may be varied 55 as desired for the reason that they form no part of the present invention, being illustrated only to exemplify the operation and arrangement of such parts as will herein-after be described as novel.

The closed end of the cylinder 1 is provided with a concentric vertical bore 7 open to the explosion chamber of the engine. The terminals of the spark coil extend into the bore 7 as shown. An annular flange 65 or shoulder 8 is formed on the outside of the cylinder 1 at a point adjacent the closed end thereof, the said shoulder or flange serving as a support for a suitable open end cylindrical valve member 9 mounted thereon and arranged to embrace or inclose the upper closed end of the cylinder. Elongated openings 10 and 11 (to-be-hereinafter designated respectively the intake and the exhaust ports of the engine) are formed in 75 the cylindrical shell or valve member 9, the said ports being adapted to register respectively with an intake passage way 12 and an exhaust passage way 13 formed in the closed end of the cylinders, each of the said 80 passage ways being open to the explosion chamber via the vertical bore 7.

As a means whereby valve member 9 may be held in place and as a means whereby the closed end of the cylinder 1 may be properly jacketed, I provide a suitable cylinder head or cap designated as an entirety by the numeral 14, the said cap being of a proper size and design whereby to fit over and upon the closed end of the cylinder. A vertical opening 15 is formed in the cap to receive the threaded shank of the spark plug 6. As before suggested, the cap 14 may be so constructed as to provide a water jacket 16, the said jacket being open to a like jacket 17 formed in the wall of the cylinder proper 1. An intake passage way 18 and an exhaust passage way 19 is formed in the cap 14, the respective passage ways being adapted for registration, respectively 100

with the ports 11 and 10. As shown, the passage way 12 is alined with the passage way 18, and the passage way 13 with the passage way 19.

5 Motion is transmitted from the crank shaft 4 of the engine to the valve member 9 through the medium of a plurality of gears and shafts. A worm gear structure 20 is formed on the outer or exterior surface of the valve member 9, the said gear structure operating in a recess or channel 21 therefor formed in the cap 14. A worm pinion 22 mounted on a horizontal shaft 23 is adapted for meshing engagement with 10 the gear structure 21. Shaft 23 penetrates the cylinder wall, the latter acting as a bearing therefor, and has mounted on its outer end a worm gear 24. Gear 24 is in mesh with a worm pinion 25 mounted at one 15 end of a vertical shaft 26, the said shaft being arranged upon the exterior of the engine, bearings 27 acting as the shaft support. A second worm pinion 28 is mounted on the said shaft 26 at the opposite end 20 thereof, the latter pinion being in mesh with a worm gear 29 mounted on a shaft 30 extending into the crank case 5 where it is directly connected to either the crank shaft 4, or, if desired, directly driven through 25 the agency thereof.

Compression springs or rings 31 fit annular grooves therefor designated 32 formed in the cylinder wall, the several grooves extending circumferentially of the 35 cylinder preferably in uniform spaced relation as shown. Each groove has arranged therein one of the compression rings 31, the rings being adapted for firm frictional contact with the inner face of the shell or rotary valve member 9. The passage way 12 is formed at a point equi-distant from the grooves 32, while the passage way 13 is likewise formed, the latter however being equi-distant from other of the said grooves. The 40 compression rings prevent, during rotation of the valve, the escape of gas. Said springs 31 may be fastened to the cylinder head or if desired, made to rotate with the rotary valve.

50 The operation of the engine is apparent from the foregoing disclosure, but to enable one unskilled in the art to readily understand the principles involved, I shall proceed to briefly describe the operation. Combustible gas is admitted to the explosion chamber of the engine by way of passage 18, port 11 and passage 12, the said port 11 being of course in registration with the respective passage ways 18 and 12. As the 55 engine or rather the piston executes its intake stroke, the port 11 is in the position last mentioned to in this manner suck in a charge of fuel. As the piston begins to recede or to execute its compression stroke, the port 11, by the rotation of the valve

member 9 is moved out of registration with the passage way 12 to in this manner effectually compress the inflow charge within the explosion chamber and vertical bore of the cylinder. At the proper moment, the 70 gas is ignited and the piston made to execute its power stroke, both the ports 11 and 10 being out of registration with the respective passage ways 12 and 13. Upon the completion of the power stroke, the piston 75 2 will execute its exhaust stroke to expel the burned gases, the port 10 having by this time been sufficiently rotated to register respectively with the ports or passages 13 and 19 forming the exhaust. The above cycle 80 of operation will remain in effect so long as the piston is propelled and so long as the shaft 26 is driven to properly rotate the valve member 9.

From the foregoing, taken in connection 85 with the accompanying drawings it will be noted that both the intake and exhaust of the engine are controlled through rotation of but a single valve; that the said valve may be removed, repaired, and replaced by 90 simply removing the head or cap 14; and that the rotary motion necessary to the operation of the shell or valve member 9 is transmitted direct from the crank shaft 4.

In reduction to practice, I have found 95 that the form of my invention, illustrated in the drawings and referred to in the above description, as the preferred embodiment, is the most efficient and practical; yet realizing that the conditions concurrent 100 with the adoption of my device will necessarily vary, I desire to emphasize the fact that various minor changes in details of construction, proportion and arrangement of parts may be resorted to, when required, 105 without sacrificing any of the advantages of my invention, as defined in the appended claim.

Having thus fully described my invention, what I claim as new and desire to 110 secure by Letters Patent, is:—

In an internal combustion engine, the engine cylinder, a relatively enlarged cylinder head having a cylindrical bore formed therein and leading to said cylinder, said head being further provided with an intake passage way and an exhaust passage way leading to said bore, a cylindrical valve member mounted to embrace said cylinder head, said valve member being provided 115 with an intake port and an exhaust port adapted for successive registration with said intake passage way and said exhaust passage way, a gear formed upon said valve member at the base thereof, a cover structure designed for arrangement over said cylinder head and said valve member, said cover structure being provided with an interior recess in proximity to said gear and with a threaded opening in its closed end 120 125 130

to register with said cylindrical bore, a means penetrating said cover and engaging said gear to rotate said valve member, a sparking means engaging in said threaded opening and extending into said bore for the purpose specified, and a plurality of pressure packing rings mounted in annular grooves therefor formed in said cylindrical

head to bear against said valve member, substantially as described. 10

In testimony whereof I affix my signature in presence of two witnesses.

DON Z. FLOWER.
